Inventor,

William Smith

By Frank A. Lehman.

Attorney

UNITED STATES PATENT OFFICE.

WILLIAM SMITH, OF OLEAN, NEW YORK.

SANITARY OR HYGIENIC CUSPIDOR.

1,408,542.

Specification of Letters Patent.

Patented Mar. 7, 1922.

Application filed April 29, 1919. Serial No. 293,473.

To all whom it may concern:

Be it known that I, WILLIAM SMITH, a citizen of the United States of America, and resident of Olean, in the county of Cattaraugus and State of New York, have invented certain new and useful Improvements in Sanitary or Hygienic Cuspidors, of which the following is a specification.

This invention relates to certain improvements in sanitary or hygienic cuspidors, the construction thereof embodying a base which serves as a container for the cuspidor, a pivoted closure for the container, a hollow column that is attached to the container or base, and manually actuated means for raising and lowering the cover which are constructed and associated to conceal the connections between the base and its cover, a part of the actuating means including a lever and a link which are movable between the side walls of a kerf formed through the rear portion of the base, as will be hereinafter set forth and pointed out in the claim.

One of the objects of my invention is to provide a covered container for a cuspidor with a single hinge connection which comprises a base provided with a kerf, a lever which is attached to the cover said lever having to one side of its fulcrum or pintle a rearwardly and downwardly extending portion that is housed between the side walls of the kerf, a curved link for connecting the lever with a rod, so that the rod when manually depressed will swing the cover upward, the kerf in the base guiding the lever and preventing lateral movement of the cover, also clearing the kerf when the cover is raised of any material which might accumulate therein and sweeping the same into the container.

The device is of primary importance in connection with hospitals, although it is desirable as well in private houses or in public places.

With the foregoing and other objects in view, the invention consists in the details of construction, and in the arrangement and combination of parts to be hereinafter more fully set forth and claimed.

In describing the invention in detail, reference will be had to the accompanying drawings forming part of this specification, wherein like characters denote corresponding parts in the several views, and in which—

Figure 1 illustrates a view in elevation with the cover open; and

Figure 2 illustrates a sectional view.

In these drawings 5 denotes a casing having a hinged cover 6, the said casing having a hollow column 9 with an extension 7 overlying a portion of the casing and secured thereto by a fastening such as a screw. The pedestal has a shoulder 10 near its upper end constituting a support for a cabinet 11, the said cabinet having apertures 12 in its bottom and an aperture 13 in its top for the reception of a cylindrical extension 14 which extension is likewise hollow so that the column and its extension constitute a guide for an operating rod 15, which operating rod terminates in a handle 16. At its lower end, the operating rod has a link 17 pivoted to it and the said link is also pivotally connected to an arm 18 of the plate 19, to which the seat 6 is fastened by fastenings 20, such as screws.

There are plates 21 secured to the casing, one on each side of a recess 21^a and a pintle 21^b is supported by the plates and constitutes a fulcrum for the arm 18 so that the arm may oscillate and carry the cover to an open or closed position as the operating rod is lifted.

The cabinet is rotatably mounted on the upper end of the column and it may be provided with closures such as the door 22. A tray 23 has an apertured boss 24 at its center to receive the extension of the pedestal and the said tray is rotatable on the said extension independently of or with the cabinet. The under surface of the seat 6 has turn buttons 25 and 26 which engage a flange 27 of a receptacle 28, which receptacle is intended to hold disinfectant and if desired, the receptacle may be provided with perforations such as 29 in its bottom and it is arranged that the disinfecting contents of the receptacle 28 may be discharged into the cuspidor 30 which is in the casing 5 when the cover is closed, it being understood that only a portion of the contents of the receptacle 28 would be discharged each time the cover is closed.

Secured to the under side of the cover 6 at a point between the receptacle 28 and the arm 18, is a depending curved guard 28', formed of any suitable material and designed to catch disinfectant, should the same drop from the receptacle 28, when the cover is in its open position. It is therefore obvious that when the cover is again moved to a closed position, the disinfectant caught

by the guard 28' will be deposited within the receptacle.

The cover for the base has associated with its under surface a guard, as shown by Fig. 2, for the purpose set forth, also incidentally to prevent powder finding its way into the kerf like recess, and should any material accumulate therein it will be ejected by the arm when the cover is raised.

10 From an inspection of the drawing and from the foregoing description, it will be apparent that if the handle 16 is pressed down, the operating rod will communicate motion to the cover and lift it so that access 15 to the interior of the cuspidor may be had whereas upon releasing the handle, the cover will be returned to its closed position by gravity.

The cabinet will be of utility for holding

medicines or for other uses and the tray 20 may be used for matches, ashes and the like.

I claim—

The combination with a cuspidor, of a container for the cuspidor, said container having a rear portion of greater thickness 25 than the sides and front, a kerf formed vertically through said rear portion, a hollow post attached to the container, a cover for the container, a member attached to the cover and provided with a pintle for engagement with the container and beyond the pintle with an arm that extends downwardly and rearwardly between the vertical side walls of the kerf, a rod maintained for reciprocation by the hollow post, and a curved link connected to the lower end of the arm and to the lower end of the rod.

WILLIAM SMITH.
